UNITED STATES PATENT OFFICE.

JOHN F. GUIDER, OF BUFFALO, NEW YORK.

PISTON FOR INTERNAL-COMBUSTION ENGINES.

Application filed June 21, 1920. Serial No. 390,407.

To all whom it may concern:

Be it known that I, JOHN F. GUIDER, a citizen of the United States, residing at Buffalo, in the county of Erie and State 5 of New York, have invented a new and useful Improvement in Pistons for Internal-Combustion Engines, of which the following is a specification.

This invention relates to improvements 10 in pistons for internal combustion engines and has for its object to produce a piston of practical, simple, strong and durable construction, whereby the objectionable noise due to side thrust of the piston in the cylinder, commonly known as piston slap, is 15 eliminated, and also the scoring of the cylinder walls, which is frequently experienced with the common types of pistons when they are fitted sufficiently close in 20 an endeavor to eliminate the piston slap, and which scoring is due to unequal expansion of the piston and cylinder, and undue heating of the bearing portions at the sides of the piston are prevented.

25 It is well known that in the operation of internal combustion engines the pressure on the piston when the connecting rod or pitman is in a position at an inclination to the longitudinal axis of the cylinder, produces a side thrust on the piston in a direction at right angles to the axis of the wrist pin which connects the pitman to the piston. This causes the side slap or noise and consequent wear on the sides 30 of the piston and cylinder which are located at opposite sides of the axial plane of the wrist pin. Various means heretofore proposed to prevent this "piston slap" are objectionable or impractical 35 from one or another standpoint. In some cases they add materially to the complication and cost of construction of the piston, and in others they weaken the piston so that it is liable to breakage, and its 40 durability and reliability are materially lessened.

45 In accordance with this invention the piston which is hollow, is provided preferably at each of the sides thereof which are at opposite sides of the axial plane of the wrist pin, with spaced, narrow slits which form between them a resilient or yielding wall portion which projects outwardly slightly beyond the adjacent, outer 50 surface portions of the piston so as to

engage the adjacent side of the internal surface of the cylinder and cushion the blow of the piston against the side of the cylinder. Each of these resilient projecting portions is connected at its opposite 60 ends with the wall of the piston and is an integral portion of the piston wall, so that while the resilient portion is adapted to yield inwardly between its ends, it is not loose or detached at either end, and is 65 therefore not liable to be broken in the operation of the engine. The projecting resilient portion can be formed in different ways, for instance, either by grinding down the surface of the piston at opposite sides 70 of the resilient portion so as to leave the latter projecting outwardly beyond the former, or by expanding the resilient portion of the wall between the slits by hammering or otherwise, to cause this portion to project slightly beyond the adjacent surface 75 portions of the piston.

The projecting resilient portion or portions can be disposed in different positions and extend in different directions within the 80 scope of this invention and several different arrangements are illustrated in the drawings.

In the accompanying drawings:

Fig. 1 is a side elevation of a piston for 85 internal combustion engines embodying the invention.

Fig. 2 is a fragmentary longitudinal sectional elevation thereof on line 2-2 Fig. 1.

Fig. 3 is a side elevation of a slightly 90 modified construction.

Figs. 4 and 5 are respectively similar side elevations of two other modifications of the invention.

Fig. 6 is an enlarged transverse section 95 of the piston on line 6-6 Fig. 5.

Referring to the drawings, A represents the piston which, as usual, is in the form of a hollow shell having a closed upper or outer end and an open inner end, and is 100 provided at opposite sides with hollow internal bearing bosses a for the wrist pin which extends diametrically through the piston and connects the pitman to the piston. b b represent the usual piston rings 105 retained in circumferential grooves in the piston near its outer end. The piston is preferably of the substantially cylindrical shape commonly employed, in which the outer end portion adjacent the piston rings 110

is a few thousandths of an inch smaller in diameter than the inner end, so that the greater expansion of this end, which gets hottest, is possible, without causing the 5 piston to bind in the cylinder.

In the construction shown in Figs. 1 and 2, the piston is provided in its side wall at one side of the plane of the bosses *a* for the wrist pin, with three parallel narrow 10 slits 10 which extend lengthwise of the piston, thus forming two longitudinal wall portions 11, 11 which are separated at their side edges from each other and from the adjacent portions of the wall of the piston by the slits 15 11. The outer surfaces of these portions 11 project outwardly slightly beyond, or are of slightly larger diameter than the outer surface of the adjacent wall portions 12 of the piston, so that they can contact with the 20 adjacent side of the cylinder, while a slight clearance will be left between the cylinder and the adjacent portions 12 of the piston. The portions 11 of the piston between the slits 10 are adapted to yield or spring inwardly under the lateral thrust to which the piston is subjected in the operation of the engine, and thereby cushion the blow of the piston against the side of the cylinder and prevent the noise which would otherwise result. The slits 10 do not extend to the ends 30 of the piston and each of the portions 11 is therefore connected at both ends thereof integrally with the adjacent wall portions of the piston, and is not in the nature of a 35 spring tongue having a free or detached end. The outer surfaces of the portions 11 are concentric with the internal surface of the cylinder and the surface of the remaining portions 12 of the side walls of the piston, and are preferably of substantially the same radius as the 40 internal surface of the cylinder. This larger diameter of the surfaces of the portions 11 can be produced, as above explained, either by grinding down the remaining portions 12 45 of the wall of the piston or by expanding the portions 11 between the slits. In practice, the difference in diameter between the portions 11 and 12 of the piston is very slight, only a few thousandths of an inch, and preferably the surfaces of the portions 50 11 are ground to leave a clearance of about one one-thousandth of an inch between them and the internal surface of the cylinder.

Figs. 1 and 2 show the yielding parts 11 55 only at one side of the piston but the piston can be and preferably is made with the yielding parts 11 at opposite sides thereof.

The construction shown in Fig. 3 is similar to that above explained, except that the 60 piston is provided at each of its opposite sides with only two slits 13 forming between them a single yielding or resilient portion 14 which projects outwardly beyond the adjacent surface portions of the piston and is

similar in arrangement and function to the 65 parts 11 above described.

In the piston shown in Fig. 4 the slits 15 extend obliquely or helically. In this case, as in the other constructions described, the portion 16 of the wall between the slits projects outwardly beyond the remaining surface portions of the wall of the piston and is of slightly larger diameter than the same, so as to conform to the internal surface of the cylinder and bear against the same while 75 leaving a clearance between the cylinder and the solid portions of the wall of the piston.

In the construction shown in Figs. 5 and 6, the piston is provided at each of the sides thereof at opposite sides of the wrist pin bosses, with two resilient or yielding portions 17 and 18 which extend circumferentially part way around the piston, one preferably in the transverse plane of the wrist pin bosses and between the same, and 80 the other near the inner end of the piston. Each of these yielding or resilient portions is formed, as in the cases of the other pistons shown, by making spaced slits 19 in the wall of the piston and expanding the portions of 85 the wall between the slits, or grinding down the remaining portions of the piston wall so as to leave the yielding or resilient portions slightly projecting. The second resilient portion 18 near the inner end of the piston 95 can be dispensed with if preferred, and in some respects it is considered best to have only the one resilient part 17 located near the piston rings *b* and the transverse plane of the wrist pin bosses. When only the one 100 transverse resilient part 17 is used, it should preferably be located at least as near the outer end of the piston as the wrist pin bosses. Otherwise it would not effectually prevent the piston from tipping on the wrist pin and its outer end slapping the side of the cylinder. In all of the constructions described the projecting or resilient portions, regardless of their form or disposition on the piston, are formed by making spaced 105 or parallel slits in the wall of the piston, and in each case the opposite ends of the resilient or yielding portion or portions are connected to the piston by integral portions of the piston walls.

By slitting the wall of the piston and causing the parts between the slits to project outwardly beyond the adjacent surface portions of the piston, as explained, the parts between the slits are capable of springing or yielding sufficiently to cushion the lateral movements of the piston in the cylinder and prevent the slap or noise due to such movements, but since the resilient parts are connected at both their ends with the piston, they are strong and durable and not liable to be broken. The projection of these parts is not so great that they have to be flexed to 110 115 120 125

permit the piston to enter or move longitudinally in the cylinder and their pressure against the surface of the cylinder is not great enough to preclude proper lubrication.

5 The arrangement of the slits and resilient portion circumferentially of the piston in or near the transverse plane of the wrist pin bosses, as shown at 17 in Fig. 5, also has a marked beneficial cooling or heat insulating 10 effect. They do not prevent the heat from being transmitted to the wrist pin bosses and adjacent parts of the piston where a relatively great bulk of its metal is disposed and where the heat is readily conducted off 15 through the wrist pin and pitman, but the slits impede heat transmission to and beyond the resilient parts 17, thus preventing undue expansion of the piston and reduction in the viscosity of the lubricant at these points.

20 I claim as my invention:

1. A piston for internal combustion engines, comprising a hollow shell having a plurality of spaced slits in the side wall thereof, said slits providing integral yielding portions in the side walls of said shell, said integral yielding portions projecting uniformly outwardly slightly beyond adjacent surface portions of the piston, a portion of at least one of said integral yielding 30 portions extending into the transverse axial plane of the pivotal connection for the pitman of said piston.

2. A piston for internal combustion engines, comprising a hollow shell having 35 spaced slits in the side wall thereof at one side of the longitudinal axial plane of the pivotal connection for the pitman, the in-

tegral portion of the piston wall between said slits projecting outwardly slightly beyond and substantially concentric with the 40 adjacent surface portions of the piston in the same transverse plane at opposite sides of said slits, said integral portion between said slits being connected at its opposite ends with the wall of the piston.

45 3. A piston for internal combustion engines, comprising a hollow shell having spaced parallel slits extending circumferentially through its side walls and part way around the same, the integral portion of the 50 piston wall between said slits projecting outwardly at uniform inclinations from the ends of the slits, beyond the adjacent surface portions of the piston in the same transverse plane.

55 4. A piston for internal combustion engines, comprising a hollow shell having spaced slits in the side wall thereof, said slits providing between them integral yielding portions in the side walls of said shell 60 which have non-yielding adjacent piston surface portions in the same transverse plane, said integral yielding portions projecting outwardly slightly beyond said adjacent surface portions of the piston, and the outer 65 sides of said yielding portions being concentric with said adjacent surface portions of the piston.

Witness my hand this 18th day of June, 1920.

JOHN F. GUIDER.
